UNITED STATES PATENT OFFICE.

BUTLER AMES, OF LOWELL, MASSACHUSETTS.

MAGNETO.

Application filed February 10, 1919. Serial No. 272,065.

To all whom it may concern:

Be it known that I, BUTLER AMES, a citizen of the United States, and resident of Lowell, in the county of Middlesex and State 5 of Massachusetts, have invented new and useful Improvements in Magneto,es, of which the following is a specification.

This invention relates to magnetos and more particularly to the construction of the 10 rotor and circuit make-and-break mechanism and to the means for securing the rotating parts together. The objects of the invention are to provide improved means for mounting circuit make-and-break mechanism on the 15 rotor of the magneto, to provide improved means for mounting a condenser on the rotor of the magneto, and to provide improved make-and-break mechanism for a magneto.

20 In the accompanying drawings which illustrate the preferred embodiment of my invention,—

Figure 1 is a side elevation of the magneto, parts being broken away to show the 25 interior mechanism in section;

Figure 2 is an end elevation of the magneto viewed from the right-hand end of Fig. 1, the end cover of the casing being open; and

30 Figure 3 is a perspective view of an improved lug forming a part of the circuit make-and-break mechanism.

The preferred embodiment of my invention illustrated in the drawings comprises, 35 in general, a casing C, a rotor R journaled in the opposite ends of the casing, the shaft S of the rotor extending from the left-hand end of the casing as shown in Fig. 1, a plurality of U-magnets M for producing the 40 magnetic field, and a lead L for conducting current from the rotor. The right-hand end E of the casing C is detachably secured to the casing by means of bolts 1 to permit the insertion of the rotor into the casing.

45 The end E of the casing is provided with an outwardly extending hub 2 upon which is mounted a housing H for the circuit make-and-break mechanism. The housing H is closed at its outer end by means of a cap 3 50 which is hinged to the housing at 4. A spring arm 5 is pivotally mounted on the outer end of a lug 6 extending outwardly from the end E of the casing for the purpose of holding the cap 3 in closed position. The 55 arm 5 normally occupies the position shown

in Fig. 1 and swings into the position shown in Fig. 2 to permit the cap 3 to be opened.

The rotor R has the same general construction as disclosed in my former application Serial No. 217,468, filed February 16, 60 1918. A recess 7 is provided in the right-hand end of the rotor and over the outer open end of this recess an end plate 8 is secured by means of machine screws 9 extending through openings in the end plate and thence 65 across the recess 7 to the body of the rotor. The end plate 8 has a hollow hub 10 extending outwardly therefrom concentrically with the axis of the rotor and around the inner end of this hub is provided a roller 70 bearing 11 for journaling the right-hand end of the rotor in the end E of the casing C. The hub 10 extends outwardly beyond the roller bearing 11 and upon the outer end of the hub is mounted the circuit make-and-break mechanism which will now be described. 75

The circuit make-and-break mechanism comprises a disk 12 disposed transversely of the axis of the rotor and provided with a 80 hollow hub 13 adapted to fit over the rotor hub 10, the two hubs being tapered so as to fit tightly together. The rotor hub 13 is provided on the outer periphery of its tapered end portion with a keyway adapted 85 to receive an indentation 14 struck up from the hollow hub 13 of the disk 12. On the outer face of the disk 12 in the central axial region of the disk is disposed a lug 15. The lug 15 has three arms 16, 17 and 18 arranged 90 in the form of a Y for securing the lug 15 to the disk 12. These arms are secured to the disk by means of rivets or screws 19 and are insulated from the disk by means of a layer of insulation 20 and from the rivets 95 or screws by means of washers and bushing. The lug 15 has a lateral arm 22 in which is mounted a switch contact 23, the contact 23 being threaded through the arm 22 so that it may be longitudinally adjusted. The 100 switch contact 24 cooperating with the switch contact 23 is mounted on the end of a bell-crank 25, the bell-crank 25 being pivotally mounted on a lug 26 extending outwardly 105 from the disk 12. The other end of the bell-crank 25 is provided with a cam member 27 adapted to engage cams 28, which are secured to the inner face of the housing H by means of screws 48, to move the switch member 24 out of contact with the switch 110

member 23, the bell-crank being urged in a clockwise direction to close the switch contacts by means of a spring 29 mounted at one end on the disk 12 by means of a lug 30 and being attached at the other end to the bell-crank by means of a screw 31. A spring arm 32 is pivotally mounted on the outer end of a lug 33 extending outwardly from the disk 12 between the arms 16 and 17 so as to swing about the axis of the lug 33 into and out of the position shown in Fig. 2. The free end of the spring arm 32 is cupped outwardly at 34 to receive the outward end of the lug upon which the bell-crank 25 is rotatably mounted so that when the spring arm is in the position shown in Fig. 2 its outer end bears downwardly on the bell-crank in the region of its pivot to hold the bell-crank on the pivot, the cup 34 being adapted to receive the projecting end of the bell-crank pivot. The lug 33 is made hollow and within the hollow of the lug is provided a current conducting brush 35 and a compression spring 36 to urge the brush 35 against the face 37 of the end member E, the brush 35 serving to ground the rotating disk 12 on the casing.

Within the recess 7 in the end of the rotor is disposed an electrical condenser 38 similar to the one described in my aforesaid application. The condenser has two end plates 50 and 51 respectively connected to alternate layers of the metallic foil or other conducting sheets comprising the body of the condenser. A ground plate 52 is separated from the end plate 51 by a layer of insulating material 53, the plate 52 having a central opening 54 therethrough. The plates 50, 51 and 52 are held tightly together by rivets 55 at the four corners of the condenser, the rivets contacting with plates 50 and 52 but being insulated from plate 51. The plate 52 is secured to end 8 of the rotor by screws. The end plates 50 and 51 are connected in bridge of the primary winding of the rotor (not shown) by means of binding posts 57 and 58, the plate 50 being grounded through the rivets 55 and plate 52 and the plate 51 not being grounded.

Projecting outwardly from the center of plate 51 through the opening 54 in plate 52 is an internally threaded tube 39. A machine screw 40 extends through an axial opening 41 in the lug 15 and threads into the tubular projection 39 on the condenser thereby clamping the condenser and the circuit make-and-break mechanism to the end plate A of the rotor, the condenser 38 being drawn against the inner face of the end 8 and the circuit make-and-break mechanism being drawn on to the outer end of the hub 10. A sleeve 43 of suitable insulating material is inserted between the tubular projection 39 and the hollow hub 10. A steel spring 44 is secured to one side of the hous-

ing H so as to extend over the end of the screw 40 and bear inwardly thereon through the medium of a brass bearing disk 45. A portion of the spring 44 is broken away in Fig. 2 and the position of the broken portion is indicated in dot and dash lines. The spring 44 is insulated from the housing H by a layer of insulation 46 and is connected to a binding post 21, the spring affording means for short-circuiting the make-and-break mechanism when it is desired to render the magnets inoperative.

The operation of my improved magneto is substantially the same as that of certain well known types and need not be described in detail. Suffice it to say that the make-and-break mechanism and condenser are rigidly secured to the end of the rotor so as to rotate therewith. The switch members 23 and 24 are normally closed and are opened by means of cams 28 four times during each revolution of the rotor, although it will of course be understood that the cams may be arranged to open the switch members two or six or any desired number of times per revolution depending upon the number of poles on the rotor, etc. It will be understood that the switch contacts 23 and 24 are connected in the circuit of the primary coil of the magneto for the purpose of normally short-circuiting the primary, and that the condenser 38 is connected in parallel with the switch contacts. The ungrounded side of the primary and condenser are connected to ground over the following circuit: Condenser plate 51, tubular projection 39, screw 41, lug 15, switch contact 23, switch contact 24, bell-crank 25, spring 29, lug 30, disk 12, lug 33, brush 35, and thence to the casing E which is grounded.

One of the cardinal features of the present invention resides in the means for mounting the make-and-break mechanism on the rotor. By telescoping the hub 13 over the hub 10 the engaging surfaces between the two hubs are disposed at a greater radial distance from the axis of the rotor than if the hub 13 were made sufficiently small to telescope into the hub 10. Thus the tendency for the make-and-break mechanism to rotate on the hub is greatly reduced, and a circumferential displacement of the keyway or indentation from the proper point in forming same will produce a smaller error in the timing of the mechanism. Moreover by making the hub 13 fit over instead of into the hub 10 the keyway on the hub may be more easily cut inasmuch as it is disposed in the outer instead of the inner periphery of the hub 10. By striking up the indentation 14 which is adapted to cooperate with the keyway in hub 10 the key connection can be made more easily and cheaply and the larger diameter of the hub

14 resulting from its fitting over instead of into the hub 10 facilitates the formation of indentation 14.

Another cardinal feature of the invention 5 comprises the lug 15 having the radially projecting arms 16, 17 and 18. By virtue of this construction the lug may be rigidly secured to the disk 12 near the outer periphery of the disk. If the collar 13 tends to 10 rotate on collar 10 the connection between the condenser and the lug 15 comprising the screw 41 would tend to rotate the disk through the medium of lug 15 thereby producing a torsional stress in the connection 15 between the lug and the disk. By providing this connection comprising rivets 19 at a considerable radial distance from the axis of the rotor there is much less danger of the connection being broken by this stress. The 20 forked arms 16 and 17 straddle the lug 33, thereby producing a symmetrical construction resulting in greater compactness and rigidity. With the lug 15 secured to the disk 12 in the aforesaid manner it is practically integral with the disk and the opening 25 for contact screw 23 may be drilled after the lug is secured to the disk and while the device is mounted in the jig employed in drilling the opening in the disk for lug 17.

30 I claim:

1. A magneto comprising a rotor, a pair of switch members, a disk secured to the end of the rotor transversely of the axis

of the rotor for supporting one of said switch members, and a lug disposed in the 35 central region of said disk for supporting the other of said switch members, said lug having a plurality of arms extending outwardly in divergent directions for securing the lug to said disk. 40

2. A magneto comprising a rotor, a pair of switch members, a disk secured to the end of the rotor transversely of the axis of the rotor for supporting one of said switch members, and a lug disposed in the central 45 region of said disk for supporting the other of said switch members, said lug having a plurality of arms extending outwardly in the form of a Y for securing the lug to said disk. 50

3. A magneto comprising a rotor, a pair of switch members, a disk secured to the end of the rotor transversely of the axis of the rotor for supporting one of said switch members, and a lug disposed in the central 55 region of said disk for supporting the other of said switch members, a second lug for holding said first switch member on said disk, said second lug being mounted on said disk at one side of said first lug, said first 60 lug having a pair of arms straddling said second lug for securing the first lug to said disk.

Signed by me at Boston, Mass., this 23rd day of January 1919.

BUTLER AMES.
